(57) **CLAIM**

The ornamental design for a window covering fascia, as shown and described.

DESCRIPTION

FIG. 1 is a top-right-rear perspective view of a window covering fascia, showing my new design;

FIG. 2 is a top-right-rear perspective view thereof, shown in a position of use with environmental brackets;

FIG. 3 is a top-right-rear perspective view thereof, showing the environmental brackets removed;

FIG. 4 is a top elevational view thereof;

FIG. 5 is a rear elevational view thereof;

FIG. 6 is a bottom plan view thereof;

FIG. 7 is a front elevational view thereof;

FIG. 8 is a left side elevational view thereof;

FIG. 9 is a right side elevational view thereof;

FIG. 10 is a left side elevational view thereof, shown in a position of use with an environmental roller shade, end bracket, curtain and carrier; and,

FIG. 11 is a left side elevational view thereof, shown in a position of use with an environmental end bracket, curtain, and carrier.

The dashed lines shown represent environment that forms no part of the claimed design. The break lines shown in FIGS. 1-7 symbolize breaks in the length of the article in which the claimed design is embodied. The appearance of any portion of the article between the break lines forms no part of the claimed design.
